Primary Examiner — Steven J Czyz(74) Attorney, Agent, or Firm — William E. Gallagher;
Andrew J. Hagerty(57) CLAIM

The ornamental design for a case for menstrual cup, as shown and described.

DESCRIPTION

FIG. 1 is a perspective view of a case for menstrual cup;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines depict portions of the article that form no part of the claimed design.

1 Claim, 7 Drawing Sheets(56)
